CHANNEL CONDUCTOR CLAMP

Hugh W. Papet, New York, N. Y., assignor to
 Anaconda Wire & Cable Company, New York,
 N. Y., a corporation of Delaware

Application June 29, 1934, Serial No. 733,048

8 Claims. (Cl. 173—251)

This invention relates to clamps for electrical conductors, such as bus bars, constructed of channel shaped beams or elements formed into a hollow conductor of rectangular or similar geometric cross-section.

5 When conductors carry powerful alternating currents vibratory or pulsating electro-magnetic forces are set up. These forces tend to cause the conductor elements to chatter in the supporting clamps, particularly in such constructions as the hollow channel type of bus bar where it is desirable to provide a longitudinal slip or sliding fit between the bus bars and the supporting members.

10 15 An object of my invention is to provide a bus bar or conductor support for the channel type of construction which will hold the channels securely against chattering while permitting longitudinal expansion, if desired.

20 25 Various features of the invention are illustrated in the accompanying drawings in which Fig. 1 is a side elevation of a channel type of bus bar and clamps embodying a preferred form of the invention; Fig. 2 is a vertical cross-section of the clamp and channel construction taken on the line 2—2 of Fig. 1; Figs. 3, 4 and 5 are respectively side, end and top views of an element of the clamp.

30 35 In my invention a pair of channel bars or elements 11 and 12 are arranged horizontally with the web vertical and the flanges at top and bottom slightly spaced and in reversed complementary relation to form a structure that is rectangular in cross-section and has longitudinally extending spaces at top and bottom to permit a free circulation of air upwardly through the interior of the conductor.

The channel bars 11 and 12 are supported at 40 intervals in their length on a support or base 13 of porcelain, or other suitable insulating material, having a central rib 14 in its upper surface to act as a spacer separating the opposed edges of the channel bar flanges.

45 50 The channels are similarly spaced and held in position by a cap 15 of insulating material having a downwardly depending rib or spacer element 16 between the opposed edges of the uppermost flanges of the channel bars. The spacing elements 14 and 16 are conveniently formed as longitudinal ribs, but it will be understood that any suitable projection or spacing means may be employed.

55 The upper element or cap 15 is secured in position and clamped or held downwardly on to the channel elements by means of clamps 17, one at

each side of the bus bar and bolted to projecting flanges 18 and 19 respectively of the base 13 and cap 15. The clamps 17 also serve to hold the channel elements 11 and 12 from sliding sidewise from their position between the base 13 and cap 15.

The clamps 17 may be of any suitable construction preferably, as shown in Figs. 1, 3, 4 and 5, of a pair of T-section columns 20 and 21 having sockets at their upper ends to receive screws 10 22 for bolting the clamps between the flanges 18 and 19, and also having connecting webs 23 and 24 at top and bottom. The webs 23 and 24 are recessed at 25 and 26 respectively on their inner sides to receive the lower and upper ends of an 15 arc shaped spring 27, the intermediate part of which bears against the outer surfaces of the channels 11 and 12.

The spring 27 holds the channels from opposite directions respectively against the central 20 spacer elements 14 and 16 with a resilient action 25 that takes up vibrational or pulsating forces and prevents the channel elements from vibrating or "chattering" between the spacer elements 14 and 16, and the inner surfaces of the clamps. At the same time it permits a longitudinal freedom of 30 motion for the channels 11 and 12 which may be absorbed in flexible connectors at intervals along the bus run to prevent buckling when the channels become heated and expand. This also relieves 35 the insulators of destructive strains due to bus expansion.

By the above invention a clamp of simple rugged construction is provided which may be very easily assembled and which holds the channel members securely in position against sidewise movements and vibrations while still permitting the necessary freedom of movement in a direction lengthwise of the channels.

It will be obvious, of course, that the invention 40 may be applied to a case where but a single channel is to be employed between upper and lower elements by a single clamp.

What I claim is:

1. A channel bus bar clamp assembly which 45 comprises a supporting base having a spacing means, a cap having a spacing means overlying that of the base, channel members arranged in pairs one on each side of said spacing means 50 between said base and said cap in reversed positions to form a hollow conductor, a pair of clamping members, one at one side and the other at the opposite side of said pair of channels connecting said cap and said base and resilient 55

means confined between said channel members and said clamping members.

2. A channel bus bar and supporting clamp assembly which comprises a pair of channel members arranged with their upper and lower flanges extending horizontally in reversed positions to form a hollow conductor and with adjacent edges of the said flanges slightly spaced, a supporting base and a cap, said base and cap having spacing ribs between the edges of said flanges, clamp members connecting said cap and said base on the outer sides of said pair of channel members and spring means reacting between said channel members and said connecting clamp members to force said channel members resiliently against said ribs.

3. A channel bus bar and support assembly which comprises a pair of channel members positioned with their upper and lower flanges arranged in reversed positions to form a hollow conductor, means between said channel members to slightly space the opposed edges of said flanges and means on opposite sides of said pair of channel members to press said channel members resiliently against said spacing means.

4. Clamping and supporting means for a channel bus bar which comprises channel members positioned with their upper and lower flanges arranged in reversed positions to form a hollow conductor, a base, a cap, said base and said cap each having a central spacing means between a pair of opposed edges of said channel members, connecting members, one at one side and the other at the opposite side of said pair of reversely positioned channel members between said base and said cap, and a spring mounted between the inner face of each of said connecting members and said pair of channel

members to force said channel members resiliently against said central spacing means.

5. Apparatus of the type described which comprises a horizontally extending channel beam, supporting means contacting the upper and lower surfaces of said beam and each having a stop, and means on opposite sides of said channel beam for resiliently pressing the flange edges of said beam against said stop.

6. Apparatus of the type described which comprises a longitudinally extending channel beam, supporting means engaging the upper and lower surfaces of said channel beam and having stops for the upper and lower surfaces each respectively of one side of said beam, a clamping means at the opposite side of said beam, and a resilient means confined between said clamping means and adjacent side of said beam.

7. Apparatus of the type described which comprises a longitudinally extending channel beam, supporting means engaging the upper and lower surfaces of said channel beam and having stops for the upper and lower surfaces each respectively of one side of said beam, a clamping means at the opposite side of said beam and an arc shaped spring confined between said clamping means and adjacent side of said beam.

8. A hollow bus bar and supporting assembly which comprises a pair of conductor elements each having upper and lower surfaces extending toward the upper and lower surfaces respectively of the opposite element, spacing means between the upper and lower surfaces of said respective conductor elements, and means on opposite sides of said pair of conductor elements to press said members resiliently toward said spacing means.
